(57) **CLAIM**

The ornamental design for a crane as shown and described.

DESCRIPTION

1.1 : Front view

1.2 : Rear view

1.3 : Left side view

1.4 : Right side view

1.5 : Top plan view

1.6 : Perspective view in an operative condition

1.7 : Partial enlarged view taken from area **1.7** in FIG. **1.6**

1.8 : Partial enlarged view taken from area **1.8** in FIG. **1.6**

The evenly spaced broken lines in the drawings depict portions of the crane that form no part of the claimed design. The dot-dash broken lines in FIGS. **1.6**, **1.7** and **1.8** outline enlarged areas and form no part of the claimed design.
